Richard B. Oliver,

ATTORNEY.

UNITED STATES PATENT OFFICE.

NORMAN H. A. NELSON, OF FLINT, MICHIGAN.

FOUNTAIN-PEN.

1,391,267.

Specification of Letters Patent. Patented Sept. 20, 1921.

Application filed May 7, 1920. Serial No. 379,560.

To all whom it may concern:

Be it known that I, NORMAN H. A. NELSON, a citizen of the United States, residing at Flint, in the county of Genessee and State of Michigan, have invented certain new and useful Improvements in Fountain-Pens, of which the following is a specification.

This invention relates to self-filling fountain pens and has for its object the production of a simple and efficient fountain pen wherein two separate compartments are employed for the purpose of permitting two different colors of ink to be retained in the pen in the separate compartments.

Another object of this invention is the production of a simple and efficient means for facilitating the filling of the pen after the bulb in either compartment has become empty.

Other objects and advantages of the present invention will appear throughout the following specification and claims.

In the drawing:

Figure 1 is a side elevation of the pen, and

Fig. 2 is a longitudinal section therethrough.

By referring to the drawing, it will be seen that the pen comprises a body formed of a primary section 1 and an auxiliary section 2. The primary section 1 is provided with an extension internally threaded collar 3 which is threaded upon an externally threaded neck portion 4 formed upon the auxiliary section 2 of the body of the pen. A pen point 5 is carried by the primary section 1 of the body and a pen point 6 is carried by the auxiliary section 2 of the body. A suitable bulb 7 is associated with the point 5 for the purpose of supplying ink to the point 5 and a suitable bulb 8 is employed in conjunction with the point 6 for supplying ink to the point 6. Suitable point holder sections 9 and 10 are employed

for the purpose of supporting the respective pen points 5 and 6. A protector cap 11 is threaded upon the point holder portion 10 as shown in Fig. 2 for the purpose of protecting the point 6. A suitable cap 12 is also threaded upon the primary section 1 of the body of the pen as shown in Fig. 2 for the purpose of protecting the pen point 5. The pen point supporting neck 9 is also provided with a threaded portion 13 formed thereon so that the cap 11 may be threaded thereon when the point 6 is used.

The compression lever 14 is pivotally mounted upon a supporting pin 15 and this supporting pin 15 is firmly clamped between the primary and auxiliary sections 1 and 2 of the body of the pen as clearly shown in Fig. 2. The compression lever 14 is also provided with upwardly curved end portions 16 as shown in Fig. 2 and these upwardly turned end portions 16 are normally seated within the channels 17 formed in the primary and auxiliary sections 1 and 2 of the body of the pen. It should be understood that when it is desired to either fill the bulb 7 or bulb 8, the compression lever 14 may be swung to the desired position thereby raising one end and lowering the other and upon releasing the compression lever 14 the suction within the tube will cause the tube to be filled with ink through the sucking of the ink from a bottle or other receptacle up through the pen point into the bulb. The primary and auxiliary sections 1 and 2 of the body of the pen are dished or cut away as indicated at 18 located adjacent the respective ends of the compression lever 14 to facilitate the insertion of the finger nail under the ends of the compression lever 14 for the purpose of swinging the lever to a proper position whereby the lever may be brought to act upon either the bulb 7 or the bulb 8.

It should be understood that the purpose of employing two separate points upon the body of the pen is to provide a means whereby red ink may be employed in one end of the pen and blue in the other, or any other desired or suitable color so that a contrast may be obtained. In this way the necessity of employing two separate pens may be overcome by retaining the two separate or distinct colors of ink in the same pen or rather in two separate compartments, each compartment being located at the opposite end of the body of the pen.

It should be understood that certain detailed mechanical changes may be employed in connection with the present invention without departing from the spirit thereof so long as these changes fall within the scope of the appended claims.

I claim:

1. A pen of the class described comprising a body having a primary and auxiliary section, means for securing said sections together, a pen point carried by each section, a reservoir bulb associated with each pen

- point, and a compression lever pivotally mounted between said sections and adapted to coöperate with each reservoir bulb for the purposes of compressing the same.
5. 2. A pen of the class described comprising a body formed of a pair of sections, a reservoir bulb mounted within each section, said body provided with an elongated slot formed therein, a pivoted lever inclosed between said sections and fitting snugly within said slot, each end of said lever being upturned for producing a compression knob adapted to engage a reservoir within the body of the pen, and each section provided with a dished-out portion located near each end of the lever for facilitating the lifting of the lever and swinging thereof to a desired position.
10. 3. A pen of the class described comprising a body formed of a plurality of sections, a lever, a supporting pin clamped between said sections and pivotally supporting said lever between said sections, each section provided with a registering slot extending longitudinally thereof for the purpose of receiving said lever, a pen carried by each section, a reservoir secured to each pen, and
15. 4. A double ended pen of the class described comprising a plurality of sections, reservoir bulbs carried by said sections, and a compression lever interposed between said sections and adapted to engage the respective bulbs for the purpose of compressing the same.
20. 5. A double ended pen of the class described comprising a plurality of sections, a reservoir bulb carried by each section, a compression lever, and a pivot support clamped between the abutting end of said sections and pivotally supporting said compression lever to permit the lever to be actuated for compressing the reservoir bulbs carried by said sections.
25. In testimony whereof I affix my signature in presence of two witnesses.
- 50
NORMAN H. A. NELSON.
